UNITED STATES PATENT OFFICE.

JACOB E. DAVIS, OF IRONTON, OHIO.

GAS-BURNER.

1,258,993.

Specification of Letters Patent. Patented Mar. 12, 1918.

Application filed June 28, 1916. Serial No. 106,482.

To all whom it may concern:

Be it known that I, JACOB E. DAVIS, a citizen of the United States, residing at Ironton, in the county of Lawrence and State of Ohio, have invented certain new and useful Improvements in Gas-Burners, of which the following is a specification.

The primary object of the present invention is to produce a gas burner which is especially adapted to consume natural gas and render its application to furnaces practicable, to which end, one feature of the invention resides in providing a plurality of gas and air mixing tubes in association with a specially constructed heat deflecting structure which, when applied to a furnace, will enable natural gas to be practicably used as fuel.

Another object of the invention is to provide a novel and economical construction of burner and to further construct the heat deflecting structure in a manner to render it especially adaptable for use in connection with this particular construction of burner.

A further object of the invention is to produce a gas burner and heat deflecting structure which may be readily applied to a conventional type of furnace by applying the same to the fire-box of the furnace through the door leading therein.

With these and further objects in view, the invention will be further described with reference to the accompanying drawings, and the points of novelty thereof set forth in the subjoined claims.

In said drawings:—

Figure 1 is a sectional view of the burner and the heat deflecting structure;

Fig. 2 is a sectional view on the line 40 2—2 of Fig. 1;

Fig. 3 is a plan view partly in section of a modified form;

Fig. 4 is a side view of the form illustrated in Fig. 3;

Fig. 5 is an enlarged perspective view of one section of the heat deflecting structure as illustrated in Figs. 3 and 4;

Fig. 6 is a section of still another form of heat deflecting structure;

Fig. 7 is an enlarged view of a portion of the burners.

Referring to the drawings in detail, the invention will be first described with reference to the preferred embodiment illus-

trated in Figs. 1 and 2, in which 1 represents the heat deflecting structure which, according to the preferred form of the present invention preferably comprises a substantially cylindrical or round hollow body, preferably constructed of fire brick. In order that it may act to produce the best results, it preferably comprises a shell having a thickened base 2, an outwardly flaring top portion 3, and a vertical wall 4, tapering on its inside toward the outwardly flaring top portion 3, the outer wall, however, being preferably perpendicular. The inner circle formed by the shell is preferably constructed air-tight, by such means as the metal cover 5 and the metal bottom closure 6. The burner which is associated with the shell preferably comprises air and gas mixing tubes constructed to surround the perpendicular wall of the shell and disposed in such a manner as to enable the flame to play against the under side of the outwardly flaring top portion 3, which portion will act to retard the flame and deflect the flame against the wall of the fire chamber of the furnace. In actual practice, these tubes will be placed a sufficient distance from the furnace wall to enable a current of air to be passed from beneath up through this space where it will be mixed with the flame. As the inner circle formed by the shell is air-tight, all the air passing through the furnace will be forced into and around the flame. By this method the combustion may be brought to a very high state of completion, and all the heat units of the gas will be utilized and discharged against the wall of the fire chamber. Furthermore, it is to be noted that the heating of the air is begun at the bottom of the fire chamber from where it is deflected on to the upper portion of the fire chamber. The particular construction of the tubes preferably comprises a manifold pipe 7 which is adapted to have a double connection to suitable gas supply pipes. This manifold pipe 7 is provided with a multiplicity of equally spaced openings 8 in its top, and directly over each opening is positioned a tube 9. Steel bands, such as 10, are provided, preferably on both sides of the tubes and support the same near their top and bottom by being electrically welded thereto. In order that the manifold pipe 7 may be

securely held in place, a series of straps 11 are employed, which are looped under the pipe and clamped thereto by a bolt or rivet 12 with the respective ends of the straps 5 fixed to the steel bands 10 supporting the tubes. With this construction of burner, a rigid circle is made surrounding the shell of the heat absorbing and deflecting structure. In order that the burner may be 10 readily applied to the furnace through the door leading into the fire chamber, the shell 1 and the burner are constructed in half section, but should it be desired, they could be constructed in quarter sections, or even 15 smaller sections. In this respect, the burners may be joined together by providing a union 13 for connecting the ends of the confronting sections of the manifold pipe 7.

For furnaces having a long fire box or 20 chamber, the burners and the heat deflecting structure will be so designed as to conveniently fit therein.

The embodiment of the invention illustrated in Figs. 3 to 5 inclusive illustrates a 25 square construction of burners and heat and deflecting structure. In this embodiment, the shell 1 is shown as constructed of four sections. The embodiment shown in Fig. 6 illustrates a section of a much smaller 30 heat absorbing and deflecting structure which would be applicable to small furnaces or even heating stoves. Fig. 7 illustrates a somewhat different manner of clamping the strap 11 to the service pipe, 35 wherein the bolt instead of passing through the pipe is shown as clamping the strap to the pipe by a bolt positioned immediately above the pipe, a suitable sleeve 14 being employed.

40 I claim:—

1. In combination, a heat deflecting structure composed of refractory material having an outwardly flaring top, a gas burner associated with said heat deflecting structure in a manner to permit of the flame being retarded by the outwardly flaring top, and deflected outward toward the wall of a fire-box of a furnace to which said heat absorbing and deflecting structure and said 45 burner are applied, said heat deflecting structure comprising a hollow shell having its inner wall tapering from the base toward the outwardly flaring top and having an outer perpendicular wall.

50 2. In combination, a heat deflecting structure composed of refractory material having an outwardly flaring top, a gas burner associated with said heat deflecting structure in a manner to permit of the flame being retarded by the outwardly flaring top, and deflected outward toward the wall of a fire-box of a furnace to which said heat absorbing and deflecting structure and said 55 burner are applied, said heat deflecting structure comprising a hollow sub-divided

shell having its inner wall tapering from the base toward the outwardly flaring top and having an outer perpendicular wall, and said burner being also constructed of divided sections. 70

3. In combination, a heat deflecting structure composed of refractory material having an outwardly flaring top, a gas burner associated with said heat deflecting structure in a manner to permit of the flame being retarded by the outwardly flaring top, and deflected outward toward the wall of a fire-box of a furnace to which said heat deflecting structure and said burner are applied, said heat deflecting structure comprising a sub-divided hollow shell closed at its top and bottom having a thickened base, an inner wall tapering from said base toward the outwardly flaring top and a perpendicular outer wall extending from the 80 base to the outwardly flaring top.

4. In combination, a heat deflecting structure composed of refractory material having an outwardly flaring top, a gas burner associated with said heat deflecting structure in a manner to permit of the flame being retarded by the outwardly flaring top, and deflected outward toward the wall of a fire-box of a furnace to which said heat deflecting structure and said burner are applied, said burner comprising a plurality of tubes, and a manifold pipe underlying said tubes and having openings in the top directly underlying each tube. 90

5. In combination, a heat deflecting structure composed of refractory material having an outwardly flaring top, a gas burner associated with said heat deflecting structure in a manner to permit of the flame being retarded by the outwardly flaring top, and deflected outward toward the wall of a fire-box of a furnace to which said heat deflecting structure and said burner are applied, said burner comprising a manifold pipe adapted to surround the thickened base 100 of the heat deflecting structure, a plurality of tubes supported over said manifold pipe, openings in said manifold pipe communicating with the openings in the tubes and means for retaining said tubes over said 110 openings. 115

6. In combination, a heat deflecting structure composed of refractory material having an outwardly flaring top, a gas burner associated with said heat deflecting structure in a manner to permit of the flame being retarded by the outwardly flaring top, and deflected outward toward the wall of a fire-box of a furnace to which said heat deflecting structure and said burner are applied, said burner comprising a manifold pipe and a plurality of openings provided in the top thereof, a series of tubes supported over said openings, a steel band for retaining a tube over an opening in the man- 120 125 130

ifold pipe, said tube supporting means comprising a plurality of straps secured to said manifold pipe and the tubes.

7. In combination, a heat deflecting structure composed of refractory material having an outwardly flaring top, a gas burner associated with said heat deflecting structure in a manner to permit of the flame being retarded by the outwardly flaring top, and deflected outward toward the wall of a fire-box of a furnace to which said heat deflecting structure and said burner are applied, said burner comprising a manifold pipe having a plurality of openings provided in the top thereof, a plurality of tubes supported over said manifold pipe with their openings registering with the openings in said pipe, a plurality of steel bands secured to said tubes and adapted to retain them in registering relation with the openings in the manifold pipe, said tube supporting means comprising a plurality of straps looped under the manifold pipe with their respective ends secured to said tubes, and means for securing the looped ends of said straps to said manifold pipe.

8. In combination, a heat deflecting structure composed of refractory material having an outwardly flaring top, a gas burner associated with said heat deflecting structure in a manner to permit of the flame being retarded by the outwardly flaring top, and deflected outward toward the wall of the fire-box of the furnace to which said heat deflecting structure and said burner are applied, said burner comprising a manifold pipe having a plurality of openings provided in the top thereof, a plurality of tubes supported over said manifold pipe with their openings registering with the openings in said pipe, a plurality of steel bands secured to said tubes and adapted to retain them in registering relation with the openings in the manifold pipe, said tube supporting means comprising a plurality of straps looped under the manifold pipe, means for securing the looped ends of said straps to said manifold pipe, said manifold pipe and said burner being constructed of divided sections and means for joining the confronting ends of said sections.

9. In combination, a hollow heat deflecting structure composed of refractory material having an outwardly flaring top, a gas burner surrounding said heat deflecting structure, said outwardly flaring top overhanging said burner adapted to retard the flame and deflect it outward toward the wall

of a fire-box of a furnace to which said heat deflecting structure and said burner are applied, said burner comprising a plurality of tubes, and a manifold pipe underlying said tubes and having openings in the top thereof directly underlying each tube.

10. In combination, a heat deflecting structure composed of refractory material having an outwardly flaring top, a gas burner associated with said heat deflecting structure in a manner to permit of the flame being retarded by the outwardly flaring top, and deflected outward toward the wall of a fire-box of a furnace to which said heat deflecting structure and said burner are applied, said heat deflecting structure comprising a hollow shell having its inner wall tapering from the base toward the outwardly flaring top and having an outer perpendicular wall, and said burner comprising a plurality of tubes, and a manifold pipe underlying said tubes and having openings in the top thereof directly underlying each tube.

11. In combination, a heat deflecting structure composed of refractory material having an outwardly flaring top, gas burner associated with said heat deflecting structure in a manner to permit of the flame being retarded by the outwardly flaring top, and deflected outward toward the wall of a fire-box of a furnace to which said heat deflecting structure and said burner are applied, said heat deflecting structure comprising a sub-divided hollow shell closed at its top and bottom having a thickened base, an inner wall tapering from said base toward the outwardly flaring top and a perpendicular outer wall extending from the base to the outwardly flaring top, said burner comprising a manifold pipe having a plurality of openings provided in the top thereof, a plurality of tubes supported on said manifold pipe with their openings registering with the openings in said pipe, a plurality of steel bands secured to said tubes and adapted to retain them in registering relation with the openings in the manifold pipe, said tube supporting means comprising a plurality of straps looped under the manifold pipe, and clamping means for securing the looped ends of said straps to said manifold pipe, said manifold pipe and said burner being constructed of divided sections, and means for joining the confronting ends of said sections.

The foregoing specification signed at Iron-ton, Ohio, this 15th day of June, 1916.

JACOB E. DAVIS.
